UNITED STATES PATENT OFFICE.

GEORGE J. MURPHY, OF BUENOS AIRES, ARGENTINA.

ROLLING MILL.

Application filed May 31, 1924. Serial No. 717,041.

To all whom it may concern:

Be it known that I, GEORGE J. MURPHY, a citizen of Irish Free State, and resident of Baradero, F. C. C. A., Buenos Aires, Argentina, South America, have invented a new and Improved Rolling Mill, of which the following is a description.

My invention relates to a rolling mill and particularly to a mill adapted to roll railway rails of a special form, said rails forming part of the subject-matter of United States Letters Patent, No. 1,365,941, granted to me January 18, 1921. Said railway rails, in order to contribute to the making of a novel railway joint disclosed in my mentioned patent, are given a terminal conformation to present an overlapping portion adapted to be disposed alongside the web of an adjacent rail and lying for the major portion beneath the head of the rail, a zone of the overlapping terminal adjacent the inner end or base thereof being of a height to lie flush with the top of the rail head. Said overlapping portion furthermore has a base flange broadened beyond the width of the base flange throughout the major portion of the rail. Also, the rail at and adjacent to the overlapping portion is formed with a web of increased thickness.

The rolling mill constituting my present invention has for its object to provide a roller assemblage of such a character that a bar, rod, or partly finished blank may be entered between the rolls at an end thereof and be caused to shift laterally lengthwise of the rolls as the blank passes between the rolls, the lengths of the rolls being such as to convert the bar into a plurality of united rails ready to be cut to form the individual rails.

The nature of my invention and its distinguishing features and advantages will clearly appear as the description proceeds.

Reference is to be had to the accompanying drawings forming a part of this specification, it being understood that the drawings are merely illustrative of one example of the invention.

Figure 1 is a side elevation of a rolling mill embodying my invention;

Figure 2 is a diagrammatic view of the rolls from that end adjacent to which the blank is introduced, the view including a diagram of the bar or rod produced by the rolls;

Figure 3 is a diagrammatic view of one of the rolls between the ends;

Figures 4, 5 and 6 are cross sections through the blank and showing the formation of the rolls to produce the different portions of the rail, the planes of the sections being indicated by the lines 4-4, 5-5 and 6-6, respectively, Figure 2.

In carrying out my invention in accordance with the illustrated example, two rolls 10 are provided on shafts 11, 12, of which the former may be considered the drive shaft and in practice having any suitable means (not shown) for driving the shaft. The shafts are journaled in standards 13 rising 70 from a suitable base 14. The rolls are formed each with spiral ribs 15, the ribs of the respective rolls contacting with each other. The rolls present continuous spiral grooves 115 conforming generally to the rail cross section and having members along the grooves to produce the said formation of the rails at the end portions.

A rod is shown diagrammatically in Figure 2, the numeral 16 representing the base flange at the normal cross section of the rail; 17, the web at the normal cross section; 117, the thickened web portion; and 18, the normal rail head. The flange is broadened at the terminal of the rail, as at 19, Figure 80 2. Also, members 20 of reduced width are produced in the bar or blank to form the overlapping terminals, said overlapping terminals having at the base thereof, as at 21, increased dimensions to rise to the 85 height of the rail head 18.

The spiral groove presents a spiral rib 22 to depress the blank fed to the rolls at the opposite sides for producing the web of the rail. At one side of the rib 22 is a spiral groove 23 to produce the base formation of the rail and at the opposite side of said rib 22 is a spiral groove 24 of a form to produce the rail head. The rolls have a length 95 to produce on a semi-formed bar or blank a plurality of connected and integral rail portions so that the finished bar requires only to be cut off to produce on the individual rail lengths the overlapping portion 20 of the required length. At the end of the subdivision of the rolls resulting in the formation of an individual rail portion in the blank is an arcuate rib 25 extending radially beyond the normal periphery of the rolls, that is to say, beyond the contacting rib 15 100 105 110.

of that roll. Similarly, in the mating roll 10 is an arcuate depression 26 materially wider than the rib 25 with which it coacts. The depression 26 as shown in Figure 4 has such dimensions in cross section as to permit the rib 25 to press the widened rail base or flange 19 into the groove and give the base flange the desired angularity relatively to the web at the overlapping part 20. At 10 the base of the rib 25, there is an arcuate rib 27 of less radius but of greater length which is adapted to enter and partially fill the general spiral groove 115 between the spiral ribs 15 of the mating roll. The depression 26 is complementary to the general groove 115, as clearly shown in Figure 4. At the terminals of each arcuate rib 25, there are auxiliary rib portions 28 of less radius than ribs 25 and so related to the adjacent portions of the groove 115 and to the rib portions 25 and 27 as to produce the higher portions 21 along the blank.

In operation, the partially finished blank is fed at that end of the rolls which is the right in Figure 1. The spiral ribs 15 and grooves 115 cause the partially finished blank to shift laterally, that is, longitudinally of the rolls as the blank is fed through the rolls; after the arcuate projecting rib portions 25 have acted upon the rail to bend down the flange at the base of the portion 20 the normal cross section of the blank is again reached and another complete rail portion formed, thus the blank has produced thereon a series of connected integral rail portions requiring only to be cut at the center of that portion of the blank or rod having the members 20. Thus a single operation of the rolls after the partial formation of the blank rods suffices to produce a series of connected rail portions to correspond with the rail referred to.

I would state in conclusion that while the illustrated example constitutes a practical embodiment of my invention, I do not limit myself strictly to the mechanical details herein illustrated, since, manifestly, the same can be considerably varied without departure from the spirit of the invention as defined in the appended claims.

Having thus described my invention, I claim:

1. A rolling mill including a pair of rolls having contacting spiral ribs and alterna-

ting spiral grooves, said rolls at said grooves 55 having a cross section to roll from a blank rod, a rail having at portions thereof the normal cross section of a railroad rail, and members along the grooves at intervals to produce joint members of reduced height 60 and width at the ends of the normal cross section of the rail.

2. A rolling mill including a pair of rolls having contacting spiral ribs and alternating spiral grooves, said rolls having at portions of the grooves co-acting members to produce on a blank rail, portions of normal cross section and having at intervals members to produce alternating with the portions of normal cross section, portions of 70 normal cross section having a reduced height and width to constitute when cut overlapping terminal rail portions.

3. A rolling mill including a pair of rolls having contacting spiral ribs and alternating spiral grooves, said rolls having on portions thereof along the grooves, co-acting members to produce on the blank rail portions of normal cross section; together with members along the grooves to produce rail 80 portions of reduced height and width at the ends of the normal cross section as well as members to produce on the blank at the said portions of reduced height and width, members to produce portions of less width than the normal but of the full height of the rail portions of normal cross section.

4. A rolling mill including a pair of rolls having contacting spiral ribs and alternating spiral grooves, said rolls having along portions thereof at the grooves, co-acting members to produce on the blank rail portions of normal cross section; together with members along the grooves to produce rail 95 portions of reduced height and width at the ends of the normal cross section as well as members to produce on the blank at the said portions of reduced height and width, members to produce zones of less width than the normal but of the full height of the rail 100 portions of normal cross section, and arcuate spiral ribs on one of the rolls, said ribs of increased radius and adapted to bend the base flange at the portion of reduced width, the other roll having depressions registering 105 with the arcuate ribs to accord with the base flange when bent by said arcuate ribs.

GEORGE J. MURPHY.
